UNITED STATES PATENT OFFICE.

JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

DESIGN FOR AN AUTOMOBILE BODY FRONT.

Application filed September 2, 1927. Serial No. 23,277. Term of patent 14 years.

To all whom it may concern:

Be it known that I, JOSEPH LEDWINKA, a citizen of the United States of America, residing at Philadelphia, in the county of Philadelphia, State of Pennsylvania, have invented a new, original, and ornamental Design for Automobile Body Front, of which the following is a specification, reference being had to the accompanying drawing, forming a part thereof, wherein—

Figure 1 represents in front elevation an automobile body embodying the design of my invention, the part forming the subject matter

ter of the design being shown in full lines, and associated parts of the body and vehicle in dotted lines;

Figure 2 is a side elevation thereof.

I claim—

The ornamental design for automobile body front, as shown.

Signed at Philadelphia, in the county of Philadelphia, State of Pennsylvania, this 19th day of August, 1927.

In testimony whereof I hereunto affix my signature.

JOSEPH LEDWINKA.
